UNITED STATES PATENT OFFICE.

EDWARD J. MOORE, OF CLEVELAND, OHIO, ASSIGNOR TO THE SHERWIN-WILLIAMS COMPANY, OF CLEVELAND, OHIO, A CORPORATION OF OHIO.

SIDE-SEAM CAN-SOLDERING MACHINE.

SPECIFICATION forming part of Letters Patent No. 733,413, dated July 14, 1903.

Application filed September 11, 1902. Serial No. 122,923. (No model.)

To all whom it may concern:

Be it known that I, EDWARD J. MOORE, a citizen of the United States, and a resident of Cleveland, county of Cuyahoga, and State of Ohio, have invented a new and useful Improvement in Side-Seam Can-Soldering Machines, of which the following is a specification, the principle of the invention being herein explained and the best mode in which I have contemplated applying that principle, so as to distinguish it from other inventions.

My invention relates to machines for soldering the side seams of cylindrical can-bodies, its object being to provide simple, economical, and efficient means for such purpose.

Said invention consists of means herein-after fully described, and particularly set forth in the claims.

The annexed drawings and the following description set forth in detail certain mechanism embodying the invention, such disclosed means constituting but one of various mechanical forms in which the principle of the invention may be used.

In said annexed drawings, Figure I represents in side elevation the working parts of a machine embodying my invention, the lower or frame part being omitted. Fig. I^a represents an enlarged detail view. Fig. II represents a front elevation of such part. Fig. III represents a vertical section taken upon the plane indicated by the line 3 3 in Fig. I as viewed in the direction indicated by the arrow in Fig. I. Fig. IV represents, on an enlarged scale, a vertical sectional view of the soldering-iron and combustion-chamber therefor, taken upon the plane indicated by line 4 4, Fig. I. Fig. V represents a partial plan and horizontal section of said combustion-chamber drawn upon an enlarged scale. Figs. VI and VII respectively represent, on an enlarged scale, side and front elevational views of the rolls and support therefor for feeding the solder to the soldering-iron, together with the means for actuating the guides for directing such solder to the soldering-iron.

A main frame A is provided with two pairs of rollers a a, which form a bearing for a

horizontally-reciprocable frame B. Two upper bearing-rollers a' a' prevent the frame B from tilting while being reciprocated. Upon the front end of said frame B is secured a cylindrical horn or can-body holder B', upon which the can-bodies are slipped and held while being soldered. A spring-actuated clamp b, Figs. I and II, is journaled upon said frame in the vicinity of said horn, as shown, and serves to hold the can-body in place while being soldered and is pedally actuated to release such body by means of a rod b' and pedal b². This clamp is placed laterally of the vertical axial plane of the horn, as shown in Fig. II, in order to be removed from the sphere of operation of the soldering-iron hereinafter described. The rear portion of the horn is provided with a flange b³ for limiting the rearward movement of the can-body while being placed in position.

Upon the rear end of frame A is journaled an oscillatory frame C, the journal being formed in a screw-rod a², which may be adjusted vertically and fixed by means of a nut a³. Upon the front of the frame C is secured, by means of a cylindrical journal, a secondary frame C', a suitable cylindrical bearing being provided in said frame C for this purpose. This secondary frame C' is secured in its bearing by suitable bolts. The bearing-axis is, as shown, made substantially parallel with the plane of oscillation of frame C, and frame C' may hence be adjusted laterally of such plane by loosening the bolts which secure it to its bearing. Upon a downwardly-extending portion c is pivoted a hanger d, which supports the rear end of a hollow cylindrical combustion-chamber barrel D. The front end of such barrel is pivotally hung upon a threaded rod d', secured to the front end of frame C' by means of nuts. These nuts permit the barrel to be adjusted in the plane of its oscillation, as is seen. The lower portion of the shell of said barrel is pierced by a longitudinal slot d², through which projects a soldering-iron d³, which extends into the combustion-chamber some distance, as is shown in Fig. IV. Suitable vents d⁴ and d⁵ are provided for admission of air and emission of

gases from said chamber. A flexible pipe E is attached to an opening d^6 in the barrel for supplying combustible gas to said chamber.

An oscillatory lever F is journaled at a point f , Fig. III, to a support F', secured on the main frame A, and carries a roller f' above such point, upon which rests the frame C, Fig. I. Said frame is provided with a cam-surface c' , which may upon oscillation of lever F be engaged by said roller to oscillate the frame C. Upon this same support F' are mounted a pair of grooved feed-rollers G and G', Figs. III and VII, connected by suitable gears and with a ratchet-wheel g, operated by a ratchet f^2 , mounted upon lever F, Fig. I, the arrangement being such as to effect intermittent rotation of the feed-rolls upon the oscillation of the lever F. To effect this oscillation, the top of said lever is provided with an adjustable collar f^3 , to which is connected one end of a rod f^4 , whose other end is attached to a standard b^4 , fixed to or forming a part of the reciprocating frame B. It is thus seen that reciprocation of frame B will effect the oscillation of lever F. The ratchet f^2 is placed so as to cause the intermittent rotation of the feed-rolls to attend the forward stroke of reciprocation of frame B, and the roller f' is related to the cam-surface in a manner such that such forward stroke will effect the downward oscillatory stroke of the frame C, as will be understood from an inspection of Fig. I. In order to vary the field of oscillation of this frame, said roller is mounted upon a bolt f^5 in a slot f^6 , such bolt being capable by means of a suitable nut of being placed and secured in various positions in said slot. Opposite ends of a helical spring H is secured to frames A and C, respectively, to counterbalance the weight of frame C and its connected parts, as will be readily understood.

Upon the rear end of frame A is mounted a reel J, upon which is wound a strip of solder in the form of a thin rod or wire. The solder strip passes into the grooves of and through the feed-rollers, one of the latter being mounted in movable spring-pressed bearings in the well-known manner to effect a pressure upon the solder sufficient to cause the latter to be fed forward a short distance upon each intermittent partial rotation of the said rollers. Upon the front of the rollers' support F' is mounted a guiding-tube K, having its rearmost opening in horizontal alinement with the grooves in the feed-rollers. Such end of said tube is supported upon a horizontally-swinging plate k , suitably hinged upon said support F', as shown in Fig. VII. The opposite or free end curves inwardly toward and terminates in the vicinity of the soldering-iron d^3 , Fig. II. A helical spring k' , Fig. VI, urges the plate forward, so as to maintain such free tube end in such position. A lever k^2 engages plate k and is fulcrumed upon the support F', Fig. VI. Frame B is

provided with a lug b^5 , secured thereto in a suitable position, which is adapted on the forward movement of said frame to engage said lever k^2 and oscillate same to actuate plate k to move the free tube end from the immediate vicinity of said soldering-iron. The solder strip upon leaving the feed-rollers passes through the guide-tube, whereby, it is seen, such strip may be intermittently fed from the free end of said tube onto the soldering-iron. A guiding-piece g' , Fig. VI, is preferably provided and secured to the support F' for guiding the strip prior to its entrance into the roller-grooves. An adjustable strap A' is provided, Fig. I, for limiting the rearward movement of the frame B.

In operation the above-described device operates as follows: The flexible pipe E is connected with any suitable source of combustible gas, which is admitted into and burned in the combustion-chamber of the barrel D. Such combustion heats the soldering-iron sufficiently to melt solder coming into contact therewith. The clamp b is raised by means of the pedal b^2 and a can-body slipped upon the horn B', so as to bring the free seam edge thereof uppermost. The pedal being now relieved, the can-body is held securely upon the horn by the clamp b. Frame B is now reciprocated. Such reciprocation may be obtained by any suitable well-known means, such as a hand-lever, suitably connected therewith. The backward stroke of reciprocation passes the can-body beneath the soldering-iron, and the latter is lowered as a result of the engagement of the cam-surface c' with the roller f' , so as to bring it into contact longitudinally with the can-body seam. This permits solder on said iron to be transferred upon and to seal such seam. The forward stroke of the frame B now being effected, the can-body is removed from beneath the soldering-iron and the latter lifted into its raised position. At the same time the feed-rolls are rotated, so as to feed the solder strip forward, and the lug b^5 engages lever k^2 and so causes the tube K to swing away from the soldering-iron. The rearward stroke of the frame is attended by the release of the lever k^2 and the swinging of said tube toward the iron as a result of the action of the spring k' . This allows the solder strip to come into contact with, be melted by, and slide along the adjacent surface of the soldering-iron, thereby distributing the solder evenly along such surface. The lug b^5 is so placed as to effect engagement of the lever k^2 during the frame B's occupancy of its forward position, whereby the solder strip projecting from the end of the tube K may be kept away from the hot soldering-iron during the inactivity of the machine, the desirability for which is obvious.

Other modes of applying the principle of my invention may be employed instead of the one explained, change being made as regards the mechanism herein disclosed, pro-

vided the means stated by any one of the following claims or the equivalent of such stated means be employed.

I therefore particularly point out and distinctly claim as my invention—

- 5 1. In a side-seam can-soldering machine, the combination of a reciprocatory can-body holder, a soldering-iron adapted to effect contact with a can-body upon such holder longitudinally and mounted upon an oscillatory frame, and means for reciprocating said holder and oscillating said iron so as to effect contact between the latter and a can-body upon said holder.
- 15 2. In a side-seam can-soldering machine, the combination of a can-body holder mounted upon a reciprocatory frame, a soldering-iron mounted upon an oscillatory frame and adapted to effect contact with a can-body upon said holder longitudinally, means for reciprocating said holder-frame and oscillating said iron-frame, to effect such contact, and means actuated by such reciprocatory movement for feeding solder to said soldering-iron.
- 25 3. In a side-seam can-soldering machine, the combination of a can-body holder mounted upon a reciprocatory frame, a soldering-iron mounted upon an oscillatory frame adapted to effect contact with a can-body upon said holder longitudinally, means for actuating said two frames to effect such contact, a reel for a solder strip, and means for feeding such strip from said reel to said iron automatically.

4. In a side-seam can-soldering machine, the combination of a can-body holder, a reciprocatory frame upon which said holder is mounted, an oscillatory frame carrying a soldering-iron and means for heating the same and provided with a cam-surface, a solder-strip reel, rolls for feeding said strip to said iron, and a lever connected with said reciprocatory frame for actuating said rolls to feed, said lever provided with means for engaging said cam-surface to oscillate said oscillatory frame.

45 5. In a side-seam can-soldering machine, the combination of an oscillatory frame, a soldering-iron oscillatorily mounted thereon, and means for adjusting such iron in the plane of oscillation.

50 6. In a side-seam can-soldering machine, the combination of an oscillatory frame, a secondary frame secured to the same in a cylindrical bearing having its axis parallel with the plane of oscillation thereof, means for securing said secondary frame in said bearing, a soldering-iron oscillatorily mounted upon said secondary frame, and means for adjustably securing such iron in its plane of oscillation.

Correction in Letters Patent No. 733,413.

It is hereby certified that Letters Patent No. 733,413, granted July 14, 1903, upon the application of Edward J. Moore, of Cleveland, Ohio, for an improvement in "Side-Seam Can-Soldering Machines," was erroneously issued to The Sherwin-Williams Company, as owner of the entire interest in said invention; that said Letters Patent should have been issued to the inventor *Edward J. Moore and The Sherwin-Williams Company, jointly*, said The Sherwin-Williams Company being the assignee of one-half interest only in said patent, as shown by the record of assignments in this office; and that the said Letters Patent should be read with this correction therein that the same may conform to the record of the case in the Patent Office.

Signed and sealed this 28th day of July, A. D., 1903.
